CONTROL SYSTEM

Ludvik Joseph Koci, Berwyn, Ill., assignor to
 Western Electric Company, Incorporated, New
 York, N. Y., a corporation of New York

Application November 12, 1931, Serial No. 574,585

1 Claim. (Cl. 236—76)

This invention relates to a control system and more particularly to a system for controlling the position of an element with respect to another element mechanically unconnected therewith.

5 An object of the invention is to provide a simple and effective control system.

In many types of furnaces, such as gas-fired furnaces, the temperature regulating means is in some cases adjusted manually in accordance with 10 a temperature indicating means. If the temperature, for instance, is too low the fuel input is increased. However, it is extremely difficult to judge how much to adjust the fuel input in order to bring the furnace to the desired temperature 15 and if it is found that the temperature passes beyond the desired value, the control must again be adjusted to reduce the temperature. It may also be necessary to adjust the fuel input to compensate for varying loads on the furnace.

20 In accordance with one embodiment of an apparatus illustrating the invention, a movable member is attached to a recording thermometer and the position of a valve mechanically unconnected with the movable member is controlled 25 by the position of the movable member.

The single figure of the drawing is a schematic view of an apparatus embodying the invention.

Referring now more in detail to the drawing, a recording thermometer 5 is shown having a 30 segmental contact member 6 attached to the end of shaft 7, which is an extension of the shaft for adjusting the position of recording pencil 8. This recording thermometer may be of any well known type, such as the recording thermometer disclosed in the patent to Brewer No. 1,356,804, 35 October 26, 1920. The segmental member 6 has a plurality of segments 9 which are substantially equal in width and separated by insulating sections 11 which are slightly wider than a brush 12 contacting with the member. The end segments 40 13 and 14 come into play for lower and higher temperatures than the intermediate sections 9 which cover the normal range. Segments 13 and 14 complete an annulus with segments 9 and are separated by an insulating section 15.

45 Motor 16 carries a segmental member 17 on its shaft 10. This segmental member has segments 19, corresponding to the segments 9 of segmental member 6, and at the ends of these 50 segments are segments 21 and 22 for low and high temperatures, respectively, corresponding to segments 13 and 14 of segmental member 6. The segments 21 and 22 are substantially the same width as segments 19 and the annulus is completed by a long segment 23 of insulating material.

The member 17 has a pair of elongated arcuate brushes 24 and 25, the ends of which are spaced apart slightly more than the width of one of the segments on this member. The segments 9, 13 and 14 are electrically connected to segments 19, 21 and 25 by conductors 26.

5 Motor 16 is provided with an armature winding 27 and a pair of field windings 28 and 29. Brush 12 is connected to one of the commutator brushes of the motor through the armature winding, to the other commutator brush and to a terminal member 31. The brushes 24 and 25 are connected through field windings 28 and 29, respectively, to the terminal member 32. The motor is a series motor and the field windings are so arranged that when one of the field windings is energized, the motor will rotate in one direction and when the other field winding is energized, the motor will rotate in the opposite direction. The motor shaft 10 carries a cam 33 engaging a stem 34 of valve 35 which controls the fuel to the furnace, the temperature of which is recorded by the recording thermometer 5.

The operation of the apparatus is as follows:

25 In the position shown the temperature of the furnace is at the proper value and brush 12 rests on the first segment 9. If the temperature of the furnace increases, the segmental member 6 will rotate in a clockwise direction, as viewed in the figure, and cause the segment 14 to move under brush 12. This closes a circuit which may be traced from terminal member 31 through the armature winding to brush 12, segment 14, segment 22, brush 25, and in series through the field winding 29 to terminal member 32. The motor 30 will thus be energized in such a direction as to close the valve 35 and at the same time cause segmental member 17 to move in such a direction as to cause the segment 22 to move to a position between brushes 24 and 25, thus breaking the circuit and stopping the motor. In a similar manner the motor is energized to rotate in the opposite direction to that just described when the second segment 9 moves under brush 12. The 35 reason for the motor rotating in the opposite direction in this case is that when the second segment 9 contacts with brush 12 in going from the position shown in the drawing, contact will be made with brush 24 and field winding 28, thereby energizing the motor to operate in an 40 opposite direction from that in which it operates when the circuit is completed through brush 25 and field winding 29.

45 It is evident that the degree of fineness of adjustment of valve 35 may be varied at will by in- 50 55

creasing the number and decreasing the width of the segments on the segmental members.

While a single embodiment of the invention has been shown, it will be apparent that many changes and modifications may be made therein without departing from the spirit and scope of the invention, and the control mechanism may be applied to many other uses besides the controlling of the temperature furnace.

10. What is claimed is:

A control system comprising a temperature responsive means, a valve for adjusting the temper-

ature, a cam for actuating said valve, a motor for actuating the cam, a contact member carried by said motor having a plurality of segments, a contact member actuated by said temperature responsive means having a plurality of segments, and circuit connections between segments of said contact members and the motor for causing the motor to directly position the cam in accordance with the position of the segments of the contact member actuated by the temperature responsive means.
